[57] CLAIM

The ornamental design for a combined ceiling fan motor housing and blade irons unit, as shown and described.

DESCRIPTION

FIG. 1 is a perspective view thereof;

FIG. 2 is a front elevational view thereof, the rear and sides being substantially identical to that shown;

FIG. 3 is a top plan view thereof; and,

FIG. 4 is a bottom plan view thereof.

The broken-line showing of environmental structure in FIGS. 1-4 is for illustrative purposes only and forms no part of the claimed design.
